CLOSURE FOR COLLAPSIBLE DISPENSING
TUBES IN THE FORM OF A PAIR OF
TRANSVERSELY SWINGING CAPS

Norton Probst, Brooklyn, N. Y.

Application August 27, 1949, Serial No. 112,806

4 Claims. (Cl. 222—92)

1

This invention relates to closures for collapsible tubes or containers for dispensing pastes, creams, shaving soap, paints and the like, where a little is used at a time and it is necessary to keep the container closed when not in use to prevent hardening of the paste around the mouth of the tube or unwanted escape of the contents. Screw caps for such purpose are in wide use, but such caps get lost and the threads get so clogged with the paste after a little usage that it becomes exasperatingly difficult to put the cap on tight.

By my invention, I provide a closure which can not become separated from the tube and lost, which can be operated by a flip of the thumb, and which, when closed, seals the paste in the tube so it can not escape if the tube is accidentally pressed when the closure is shut.

My closure is preferably in the form of a pair of transversely swinging or rotatable caps, one above and the other below the neck of the tube, but closely fitting an elongated opening in the top of the tube. Both caps are secured to a common vertical pin extending through the top of the container, the top cap operating both as a thumb piece for turning both caps and as a top closure fitting over the top of the aperture through which the paste is extruded. The bottom closure prevents paste from being accidentally squeezed out between the top of the tube and the top cap, by a sealing valve action. My improved closure may be made up as a separate cylinder or ferrule, insertable in the top of the container and having two holes therethrough, one for the extrusion of the paste and the other forming a bearing for the rod connecting the hinged top and bottom caps. Or the top or neck of the container itself may be provided with the necessary apertures.

Referring to the drawings showing several forms my invention may assume:

Fig. 1 is a perspective view of a collapsible container, with my improved closure thereon;

Fig. 2 is a vertical section through the top of the container, showing the closure in the open position;

Fig. 3 is a perspective view of the same;

Figs. 4 and 5 are two perspective views of the insert I use in one form of my invention, which mounts my closure—Fig. 4 showing the same closed and Fig. 5, open;

Fig. 6 is a sectional view of a modified form of my invention in which the top of the container itself forms the mounting for the closure;

Fig. 7 is a vertical section of the same, showing the cap open;

Fig. 8 is a perspective view similar to Fig. 1, showing a safety seal broken open, that may be used on new tubes. This seal is shown unbroken in Fig. 1.

In the drawings, a typical collapsible container is shown at 1, which is provided with a top or neck portion 2 having a hole 3 therethrough, through which the paste is squeezed when in use. According to my invention, I make the neck 2 of substantial length inside so as to shape the extruded paste into a uniform column and make both top and bottom 4 and 5 smooth and flat to cooperate with swing-away caps or closures 6 and 7, one on the outside and the other inside the tube. Both caps are preferably secured to a hinge pin 8 extended through a second hole in the neck, and the upper cap is preferably thickened and knurled to facilitate its being used as a thumb piece.

Normally both caps are closed as shown in Figs. 1, 6, and 8, but when the user desires to use the paste, he turns the top cap with the thumb as shown in Figs. 2, 3, and 7 and squeezes the tube. When in place, thus effectively preventing escape of the paste, even if the tube be squeezed, since the bottom cap or closure is pressed tight against its seat by pressure of the paste.

According to my preferred method of making my improved tube invention, I construct the neck portion in two main parts, namely an outer neck formed as a part of the tube itself and hence of soft metal and a cylindrical insert or ferrule 10 of harder metal (see Figs. 4 and 5) pressed into the hole in the neck as shown in Fig. 2. The insert has a hole 3 of moderate size therethrough to act as a guide for the extruded paste and a smaller hole for the hinge pin 8 to which are secured the two caps 6 and 7. A smooth, snug fit is provided between the top and bottom of the insert and the caps. Or the neck may simply be made in one piece as shown in Figs. 6 and 7.

To insure the buyer that each tube purchased has never been used, I may place around the outside of the neck and the top cap, a plastic seal ring 11 (Fig. 1), which must be torn or cut before the cap can be turned to one side to uncover the hole 3.

From the foregoing, the advantages of my invention over the screw cap dispensing tubes will be apparent. To open and use the tube, one hand only is needed, since the thumb can turn the cap to open it as the fingers of the same hand squeeze the tube, thus leaving the other hand free to hold a toothbrush. The top also always

remains clean and free of hardened paste, as none can escape when both caps are closed.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. A collapsible tube for dispensing paste and like substances by squeezing the tube having a top with a neck portion having an elongated hole therethrough, a hollow ferrule having a press fit therein, the paste being extruded through the hole in said ferrule, inner and outer covers for said hole, the former being within the tube and the latter without, said covers being secured to a common pivot pin extending through a second hole in said ferrule and in the closed position fitting over the top and bottom of the ferrule, whereby the hole is closed both inside and out when the tube is closed.

2. A collapsible tube for dispensing tooth paste and like substances by squeezing the tube, having a neck portion extending both beyond and within the tube proper, said neck having an elongated axial hole extending therethrough through which the paste is extruded in a ribbon or rope upon squeezing, said neck having smooth raised surfaces at top and bottom, and a pair of closure caps pivoted on said neck above and below said neck so as to swing across and tightly close both ends of the hole by resting firmly against said top and bottom surfaces, said caps being secured to a common hinge pin to one side of said hole so that moving the outer cap also moves the inner cap.

3. A collapsible tube for dispensing paste and 40

the like as claimed in claim 2, having a detachable seal engaging both the neck of the tube and upper cap to prevent opening until desired for use.

- 5 4. A collapsible tube for dispensing tooth paste and like substances by squeezing the tube, having a neck portion extending both beyond and within the tube proper, said neck having an elongated axial hole extending therethrough through 10 which the paste is extruded in a ribbon or rope upon squeezing, said neck having smooth raised surfaces at top and bottom, and a pair of closure caps pivoted on said neck above and below said neck so as to swing across both ends of the hole 15 and rest firmly against said top and bottom surfaces to seal the hole at both ends, said caps being secured to a common hinge pin to one side of said hole so that moving the outer cap also moves the inner cap, and a seal engaging both 20 the neck of the tube and upper cap to prevent opening until desired for use.
